ILLUMINABLE SCREWDRIVER

Sidney Blum, New York, N. Y., assignor to Oxwall Tool Co., Ltd., New York, N. Y., a corporation of New York

Application October 2, 1956, Serial No. 43,192

Term of patent 14 years

(Cl. D93—4)

Fig. 1 is a plan view of an illuminable screwdriver embodying my new design;

Fig. 2 is a plan view thereof as viewed at an angle of ninety degrees from that shown in Fig. 1; and

Fig. 3 is a view thereof from the blade end.

I claim:

The ornamental design for an illuminable screwdriver, as shown.
